UNITED STATES PATENT OFFICE

JOSEPH ZUBATY AND LUCIAN B. SMITH, OF FLINT, MICHIGAN, ASSIGNORS TO A C SPARK PLUG COMPANY, OF FLINT, MICHIGAN, A COMPANY OF MICHIGAN

DECARBONIZER

Application filed April 17, 1931. Serial No. 530,872.

- This invention relates to carbon removing devices for use on internal combustion engines, particularly the engines of automotive vehicles.
- 5 The object of the invention is to provide a device which will supply a liquid carbon removing compound to the combustion chamber and cylinders of the engine to remove the carbon therefrom.
- 10 In carrying out the invention, a bracket is mounted at the dashboard of an automotive vehicle. A container holding a carbon remover is removably mounted on the bracket and a pipe connects the bracket and container to the intake manifold of the engine. A reciprocable plunger, spring held in one of its extreme positions, is mounted on the bracket and is adapted to be inwardly pressed to puncture or make a hole in the container which will allow the liquid carbon remover to flow from the container and be drawn into the intake manifold for delivery to the combustion chamber and cylinders of the engine.
- 15 The bracket has a special configuration and is provided with a recess. The container has an extension which fits into the recess when the container is mounted on the bracket. The slideable plunger has a pointed or sharpened edge which is adapted to pierce or make a hole in the extension to allow the carbon remover to flow from the container. When the plunger is inwardly pressed to pierce the container walls, the liquid flows from the container into a space between a reduced portion of the plunger and the wall of the bracket in which the plunger is mounted. When in inwardly pressed position, the reduced portion mates with an opening in the bracket, which opening is connected to the pipe which delivers the compound to the manifold. The plunger is also provided with a bore which extends in an axial direction thereof and also has an opening which communicates with the bore. When the plunger is inwardly pressed, the plunger opening mates with an opening in the bracket to allow air to flow to the interior of the container. The purpose of this air flow is to prevent the formation of a vacuum in the container and to allow for a ready flow of the carbon removing liquid to the cylinders.
- 20 On the drawing:
- Figure 1 shows the invention applied to the internal combustion engine of an automotive vehicle.
- Figure 2 is a sectional view through the bracket and container separated from the vehicle.
- Figure 3 is an enlarged sectional view of a portion of the structure of Figure 2 but showing the plunger depressed.
- Figure 4 is a perspective view of the cutting end of the plunger.
- Referring to the drawing, the numeral 2 indicates an automotive vehicle as a whole. The vehicle has the usual dashboard 4, toe board 6, and floor board 8. The engine is indicated as a whole at 7, the fan at 9, the fan pulley at 10. The engine has the usual intake manifold 12, the carburetor 14 and riser 16 leading from the carburetor to the manifold. The exhaust manifold is shown at 18.
- The bracket 20 of the carbon remover of the invention is mounted on the dashboard 4 and secured in place by means of bolts and nuts 11 fastened through the openings 19 in a wall of the bracket.
- The bracket has the shelf portion 22 extending horizontally from the wall of the bracket and a recess 24 is provided as shown in Figures 2 and 3. The bracket has the lateral ears 26 and the container for holding a carbon remover 28 is seated on the bracket. The container has the extension 30 at one of its ends, which extension is adapted to fit in the recess 24. A suitable gasket 32 is positioned between the container and the shelf 22 and rests in a groove 34 in the shelf. The strap 36 extends over the top of the container and has slots or openings in its ends for the reception of the screwthreaded ends of bolts 38. The shanks of the bolts are passed through openings in the ears 26. Wing nuts 40 are screwed on the threaded ends of the bolts and firmly press down on the strap 36 rigidly to hold the container in place on the shelf 22.
- The bracket 20 is provided with a bore 100

42, a portion of which is enlarged at one end as indicated at 44. The bracket has the opening 46 communicating with the bore 42 and a second opening 50 for the reception 5 of a guiding pin 48. A plunger 52 fits into and is adapted to slide in the bore 42. The plunger has the elongated slot 54 in which the end of the pin 48 is received. The pin 48 and slot 54 prevent the plunger from rotating in its bore 42 but permit of its reciprocation within the limits of the slot.

At the junction of the enlarged portion 44 with the bore 42 proper, a packing 56 is provided. The packing is held in position by 15 means of the member 58 and by the coil spring 60 retained about the plunger 52 between the member 58 and the plunger head portion 62. The spring 60 urges the plunger 52 to the position shown in Figure 2.

20 The plunger 52 is hollow or has a bore 64 at its inner end and has an opening 66 which leads to the bore 64.

The extreme inner end of the plunger is tapered as shown at 68, the tapered portion 25 having a sharp edge 70, the purpose of which is to cut, puncture or make a hole in the extension 30 of the container 28 when the plunger is inwardly pressed, as shown in Figure 3.

30 The plunger has a reduced portion 72 intermediate its ends but formed closely adjacent the tapered end 68. The purpose of the reduced portion 72 is to allow for the outflow of the carbon remover when the hole has been 35 punched by the inward movement of the plunger.

The bracket is provided with an opening 74, a portion of which is screwthreaded for the attachment of the pipe 76 which leads to 40 and is attached substantially to the central portion of the intake manifold 12 as at 78. When the plunger is in its innermost position as shown in Figure 3, the reduced portion 72 will mate with the opening 74 to allow the 45 carbon remover in the container 28 to flow to the engine.

When the plunger is in its innermost position as shown in Figure 3, it is also to be noted that the opening 46 in the bracket 20 mates 50 with the opening 66 leading to the bore 64 of the plunger 52. The purpose of this structure is to allow air to enter the opening 46 and pass through the opening 66 and bore 64 to the interior of the container. If no air 55 passage were provided, the flow of the carbon remover to the engine would tend to create a vacuum in the can and necessarily retard the flow.

The operation of the device is as follows: 60 When the automobile reaches the end of its run and is standing in the garage, the engine is not shut off but is allowed to continue to run at a relatively high speed with substantially closed throttle. The operator then 65 presses his foot on the head 62 of the plunger-

er and forces it inwardly from the position of Figure 2 to that of Figure 3. This will puncture the container and make an opening 77 therein and, owing to the high suction in the intake manifold 12, the carbon remover 78 in the container 28 rapidly will be withdrawn through the chamber or passage formed by the reduced portion 72, through the opening 74 and pipe 76, into the intake manifold 12 and to the combustion chamber and cylinders of the engine. Owing to the high degree of suction or pull exerted on the carbon remover by the suction in the intake manifold, the air from the outside will freely enter through the openings 46 and 66 to the bore 64 and into the container so that all of the liquid in the container 28 quickly will be discharged into the engine. The container 28 contains only enough carbon remover or carbon solvent for one charge and when this charge has been delivered to the engine, the engine will choke and stop. The carbon remover is allowed to remain in the engine for a considerable period. To allow the carbon remover to stand over night is sufficient and desirable. In the morning, the engine is started in the usual way and owing to the action of the carbon remover or carbon solvent, the carbon in the combustion chamber and cylinders has been dissolved or loosened 95 so that it will now be forced out of the engine into the exhaust pipe by the operation of the engine in the usual way.

After the can has been exhausted of its contents, the wing nuts 40 are loosened to allow the removal of the strap 36. The container is then removed and thrown away and a new container put in its place. The device is now ready for a second operation and may be used when desired.

We claim:

1. In a carbon removing device for application to an internal combustion engine, a bracket permanently mounted relative to the engine, said bracket having a recess, a container for a carbon remover mounted on the bracket, a portion of the container extending into the recess, means on the bracket to puncture the portion of the container extending into the recess, manually operable means to operate said first-named means after the container has been mounted on the bracket, and means constraining the carbon remover to flow to the engine.

2. In a carbon removing device for application to an internal combustion engine, a bracket permanently mounted relative to the engine, said bracket having a recess, a container having a carbon remover mounted on the bracket, a portion of the container extending into the recess, a reciprocable plunger mounted in the bracket to puncture the container, and means constraining the carbon remover to flow to the engine.

3. In a carbon removing device for ap-

lication to an internal combustion engine, a bracket permanently mounted relative to the engine, a container for a carbon remover mounted on the bracket, a reciprocable plunger on the bracket to puncture the container, and means constraining the carbon remover to flow to the engine.

4. In a carbon removing device for application to an internal combustion engine, a bracket permanently mounted relative to the engine, said bracket having a recess, a container for a carbon remover mounted on said bracket, an extension on said container extending to said recess, means on said bracket to puncture said extension, manually operable means to operate said first-named means after the container has been mounted on the bracket, and means constraining the carbon remover to flow to the engine.

5. In a carbon removing device for application to an internal combustion engine, a bracket permanently mounted relative to the engine, a container for a carbon remover mounted on said bracket, a plunger mounted in said bracket, means resiliently retaining said plunger in retracted position, said plunger adapted to be moved against the force of the spring to puncture the container, and means constraining the combustion remover to flow to the engine.

6. In a carbon removing device for application to an internal combustion engine, a bracket permanently mounted relatively to the engine, a container for a carbon remover mounted on the bracket, a reciprocable plunger mounted in the bracket, means on the plunger to make an opening in the container on reciprocation of the plunger, and means restraining the carbon remover to flow to the engine.

7. In a carbon removing device for application to an internal combustion engine, a bracket permanently mounted relatively to the engine, a container for a carbon remover mounted on the bracket, a reciprocable plunger mounted in the bracket, means on the plunger to make an opening in the container on the reciprocation of the plunger, means forming an air inlet to the container when the opening has been made, and means constraining the carbon remover to flow to the engine.

8. In a carbon removing device for application to an internal combustion engine, a bracket permanently mounted relative to the engine, a container for a carbon remover mounted on the bracket, a hollow reciprocable plunger mounted in the bracket, one end of said plunger adapted to make

an opening in the container on reciprocation of the plunger, means constraining air to enter the hollow plunger and enter the container when the opening has been made, and means restraining the carbon remover to flow to the engine.

9. In a carbon removing device for application to an internal combustion engine, a bracket permanently mounted relative to the engine, a container for a carbon remover mounted on the bracket, a reciprocable plunger mounted in the bracket, said plunger having a passage extending axially thereof and a lateral opening communicating with the passage, means to make an opening in the container on the reciprocation of the plunger, said bracket having an opening adapted to mate with the opening in the plunger to constrain air to enter the container when the opening has been made, and means constraining the carbon remover to flow to the cylinders.

10. In a carbon removing device for application to an internal combustion engine, a bracket permanently mounted relative to the engine, a container for a carbon remover mounted on the bracket, a reciprocable plunger mounted in the bracket, means to make an opening in the container on the reciprocation of the plunger, a reduced portion on the plunger, said bracket having an opening mating with the reduced portion when the plunger is pressed to make the opening, said reduced portion and opening constraining the carbon remover to flow to the engine.

11. In a carbon removing device for application to an internal combustion engine, a bracket permanently mounted relative to the engine, a container for a carbon remover mounted on the bracket, a reciprocable plunger mounted in the bracket, said plunger having a bore extending in an axial direction, a reduced portion on said plunger, means on said plunger adapted to make an opening in the container upon the reciprocation of the plunger, said plunger having an opening leading to the bore thereof, said bracket having an opening mating at times with the plunger opening to form an air passage to the interior of the container, said bracket having a second opening mating at times with the reduced portion to constrain the carbon remover to flow to the engine.

In testimony whereof we affix our signatures.
